WIRE-FENCE MACHINE.

No. 875,859.

Specification of Letters Patent.

Patented Jan. 7, 1908.

Application filed September 11, 1903. Serial No. 172,745.

To all whom it may concern:

Be it known that we, PETER W. SOMMER, JOSEPH W. SOMMER, and WILLIAM SOMMER, citizens of the United States, residing at 5 Peoria, in the county of Peoria and State of Illinois, have invented certain new and useful Improvements in Wire-Fence Machines; and we do hereby declare that the following is a full, clear, and exact description of the invention, which will enable others skilled in the art to which it appertains to make and use the same.

This invention has reference to wire-fabric making machines, and relates to machines of 15 the class for manufacturing what is known as the "staggered - stay" fencing. A fencing consisting of longitudinal strands of wire tied together in pairs by transverse strands or stays that are wound at their ends about two 20 of the longitudinal strands, the stays being arranged in break-joint fashion.

One of the objects of the invention is to secure the feeding of the strand-wires through coilers disposed between two rows of stay- 25 feeding devices; said stay - feeding devices comprising hoppers formed with reciprocating slides carrying the stay-sections, and revoluble carriers for depositing the sections of the stays into position to have their ends 30 coiled around adjacent longitudinal wires.

A further object of the invention is a new and improved pulling - out mechanism for uniformly advancing the several strand-wires, attached to adjustable operative devices whereby the spaces between the stays 35 may be lengthened or shortened; and combining therewith suitable take-up devices, and a registering device operated direct from the take-up devices.

More particularly does the invention herein relate to improvements upon a machine filed by us on September 11, 1903, Serial No. 172,744, wherein claims are made upon the stay - feeding devices and component parts; 45 and these features are incorporated in the present application to show the relative arrangement and combination of such parts or mechanism with the improvements upon which claim is made.

Further objects and aims of the invention 50 will be further understood, from the following specification together with the accompanying drawings forming a part thereof, in which:—

Figure 1 is a plan view on a greatly reduced scale of our improved machine; Fig. 2 55 is a side elevation of the same from one side;

Fig. 3 is a side elevation of the same from the opposite side; Fig. 4 is a front elevation of the machine somewhat enlarged, and with parts broken away; Fig. 5 is an enlarged elevation showing the adjustable connection between the oscillating frame and eccentric rods. Figs. 6 and 7 show two modified constructions of means which may be employed for oscillating the pull-out mechanism. 60 65

Referring to the several views of the machine 1, indicates a ground base, a portion of which is covered with flooring 2 on which an operator may stand. At the forward end of the base are arranged the standards 3 supporting a bed-plate 4 which is disposed transversely of the bar 1. 70

Journalized in the bed-plate and protruding up through the same a suitable distance is provided a series of coilers 5 having the longitudinal openings 6. On the lower end of the coilers is secured a spiral gear (not shown) each of which intermeshes with a spiral gear 7 on a longitudinal shaft 8 journalized in suitable bearings secured beneath the bed-plate 80 or frame. The coilers are disposed vertically and at graduated distances apart for the purpose of producing a fabric having a graduated mesh from top to bottom; but it is understood the coilers may be arranged at 85

uniform distances and operated with as good results. Each alternate coiler rotates in an opposite direction and to accomplish such rotation alternate gears 7 are rights and lefts, and are so arranged that the sections of a 90 stay spanning the alternate spaces between the strands in a line are fed simultaneously and alternately; which brings the ends of adjacent stay - sections, although extending laterally in opposite directions, to be actuated successively by the same coilers and directs all such coils around the same strand-wires in the same direction, which may be over or under. The coilers are constructed 95 somewhat similar to those illustrated and described in the copending application referred to and it is not thought necessary to go into or show the details thereof in this application.

Supported on the bed-plate upon opposite 105 sides of the coilers 5 is seen a series of hoppers or receptacles, conforming substantially to those described in the application referred to, having the side supports 10 with in-turned front and rear lips 11 forming sectional front and rear walls. They are further provided with the inclined reciprocal 110

slides or bottoms 12. The outside portions of the slides or bottoms 12 are attached to the frames 13 and the latter at their extreme outer ends have the angular extensions 14 engaged by means for reciprocating the slides 12.

15 indicates a pair of parallel arranged shafts journaled in suitable boxings. On these shafts are carried a series of disks or feeders 16 provided with notches 17 at intervals in their peripheries. The disks are so disposed on the shafts that there are two in front of each hopper, one at each end thereof.

For a better understanding of the device; 15 the coilers 5 are arranged in a row extending longitudinally and central of the bed-plate 4 with their upper portions protruding up through the bed-plate. The hoppers are alternately disposed upon opposite sides of 20 the coilers with the coilers adjacent to the inner faces of the disks 16, and the disposition of the hoppers is such, that from the hoppers on one side of the coilers is fed short stay-sections, or stays in break-joint fashion 25 adapted to be coiled around the first and second strand wires, the third and fourth strand wires, etc., while from the hoppers on the other side is fed short stay-sections or stays in break-joint fashion adapted to be 30 coiled around the second and third strand wires, the fourth and fifth strand wires, etc. The stay-feeding devices of the hoppers constituting a row upon opposite sides of the coilers are timed in their movements to feed 35 alternately the stay-sections, which in a completed fabric presents a "staggered-stay fence."

The features above enumerated, as suggested, are all more or less similar to those 40 described in the application referred to, and the mode of placing and feeding the stay-sections from the hoppers to the disks and from the disks to the coilers is the same as in the application referred to, and plungers as 45 seen at 18 are provided in the hoppers to control and regulate the supply of the stay-sections to the revolute carriers.

Referring to the shaft 9 which is a driving shaft, the same carries on one end the driving 50 pulley 19 and the sprocket wheel 20, the latter by a chain 21 connecting with a sprocket wheel 22 drives a shaft 23. On the opposite end of shaft 9 is eccentrically carried a rod 24, which at its opposite end is connected to a link 25, which said link is carried by one of the shafts 15, and has the integral extension 55 26. To the extension 26 is attached a coupling rod 27 which at its opposite end is attached to a link 28 which is carried by the 60 opposite shaft 15. On each of the shafts 15, which it is understood carry the disks 16, is carried a ratchet wheel 29. The teeth of these ratchet wheels are engaged by spring-pressed pawls (not shown) having connection 65 with the arms or links 26 and 28. There

are also carried by the shafts 15 the disks 30 having the corrugated or rolling peripheries 31. Coating with such disks are the extensions 14 of the frame parts 13 through the rollers 32 carried by the extensions 14. The inner end of the extensions 14 are bifurcated, although not shown, to guide the extensions 13 in their movement. Thus it will be seen, by rotating the shaft 9 movement will be imparted to the shafts 15 through the ratchet 70 and pawl movement, and rotate the shafts toward each other, imparting rotation to the disks in a step by step movement and through the disks 30 and rollers 32 reciprocate the bottoms 12 of the hoppers. Springs 80 as at 33 connected with the opposite frame parts 13 serve to return the bottoms after movement by the disks 30. These features as well as those referred to, relating to the stay-section feeder construction are alike 85 shown in the application referred to, and in detail.

Referring now to the rear of the machine, a frame support is provided by the standards 34 and 35 extending up from the base 1. To 90 these supports are journaled the transverse shafts 36, 37, 38 and 39. On these shafts are carried taking-up rollers or spiders 40 which also serve to crimp the strand wires, and by the following devices are driven continuously. 41 is a driving chain leading from a sprocket 42 on the shaft 23 to a sprocket wheel 43 on a cross-shaft 44. The speed is here regulated through gearing 45, 46 and 47; the latter carried by the shaft 36 100 and power imparted from shaft 36 through gears 48, 49, 50 and 51 carried by the shafts 36, 37, 39 and 38 respectively. The taking-up rollers or spiders are directly connected with a registering or tallying device for registering the number of feet or rods of fence made by the machine. A suitable tallying device indicated as 51 is operated by a chain 52 from a sprocket 53 on one end of the take-up shaft 37 (see Fig. 2).

52^a denotes a pulling-out mechanism composed of suitable beams having a pivotal connection on a shaft or spindle 53^a with the upper end of the frame 34 see Fig. 1 in which boxings 54 are provided secured to 115 the upper ends of standards 34 in which shaft 53^a is journaled. On the shaft 53^a is also seen a roller 55. The forward end of the frame 52^a extends across and above the hopper supports and coiling devices and carries a roller 56 on a shaft 57 journaled in the frame, the roller being similar to that shown at 55. 58 indicates reciprocal rods carried upon opposite sides of the machine and at their lower ends eccentrically connected with the opposite ends of the operating shaft 23, their upper ends adapted to be adjustably connected, see Fig. 5, with the forward ends of the beams forming the frame 52^a, through the slidable connections 120 125 130

59. The purpose of such slidable connections with the frame 52^a is, to shorten or lengthen the movement of the frame 52^a which is oscillated by the movement of the 5 rods 58, to increase or decrease the distance between the stays coiled around the strand-wires. It being understood that it is necessary or desirable to provide for the manufacture of a fabric, some of which shall have 10 the stays spaced four inches apart, and others from four inches on up. The strands of the fabric leaving the coilers are directed upwardly and over the roller 56 across to and down around the roller 55, around a roller 15 60 journaled in the standards 34 to and around the rollers or spiders 40 on the shafts 36, 37, 39 and 38 respectively, and from the roller or spider 40 on shaft 38 to a wrapper 61 whose shaft is journaled in bearings 62 20 on the base 1. In Figs. 1 and 3 is seen the means actuated by suitable power devices for operating the wrapper.

It will now be understood during the operation of the machine and the feeding of the 25 strand-wires through the coilers, the shaft 23 is continuously rotated, which at predetermined periods through the eccentric rod connections 58 therewith the forward end of the pulling-out frame 52^a will be alternately 30 raised and lowered or oscillated on its pivot 53^a, a given distance, governed by the adjustable connection of the slidable parts 59, as has been described. The raising of the 35 pulling-out frame 52^a uniformly draws an equal amount of the several strands through the coilers; the lowering of the frame 52^a preparatory to drawing the strand wires through the coilers will leave some slack in the wires, and it is during this interval in lowering the 40 frame that the stay-sections are brought coincident and coiled around the strand wires. The taking-up rollers or spiders and wrapping devices being continuously driven take care of the finished fabric and take up the 45 slack in the fabric during the interval of lowering the frame 52^a, which pulls the wires taut. The opposite end of the pulling-out frame 52^a is connected by a yielding tension device 63 with the base 1, for the purposes 50 apparent.

In Figs. 6 and 7 we have illustrated two other modes of oscillating the frames 52^a through the rods 58 and connecting devices with the shaft 23. In Fig. 6 a cam 63 is attached to the opposite ends of shaft 23, the 55 acting faces of which engage the rollers 64 on short spindles 65 fixed in a frame part 66 to which the lower end of the rods 58 are secured. A slot 67 is provided in the frames 60 66 through which the shaft 23 protrudes, and by this means guides the rods 58 in their movement. In Fig. 7 is seen a crank movement for reciprocating the rods 58, consisting 65 in providing the cranks 68 attached to the ends of shaft 23 and said cranks are pivotally

connected at 69 with parts 70 to which the lower ends of the rods 58 are secured. Thus it will be seen various methods may be employed for reciprocating the rods 58 and together with the adjustable connection at 59 70 with frame parts 52^a the desired results may be easily and readily accomplished.

We claim:—

1. In a wire fence machine, the combination of a bed frame, a plurality of coilers 75 mounted for horizontal rotation on said frame, standards extending up from the frame to the rear of the coilers, oscillating supports pivotally attached to the upper ends of the standards, and means connected 80 with the forward ends of the oscillating supports over which the finished fabric is carried.

2. In a wire fence machine, means for feeding strand-wires, means for feeding stay-wires thereto, a pulling-out device for intermittently advancing the strand-wires in equal lengths, and means for lengthening or shortening the stroke of such pulling out device and thereby increase or shorten the 90 space between the stays of the fence.

3. In a wire fence machine, the combination of a bed frame, a series of vertically disposed coilers rotatably mounted at one end of the frame, a pair of standards extending 95 up from the said bed-frame, a pair of longitudinal and parallelly disposed frames pivotally attached to the upper end of the bed-frame, means adapted to oscillate the same, and rollers supported by the frames over 100 which the finished fabric is carried.

4. In a wire fence machine, the combination of a plurality of coilers through which strand-wires are fed, mechanism for feeding stay-sections to said coilers, pulling-out 105 mechanism coöperating with said coilers comprising a pivoted frame carrying means around which the strand-wires are carried, an operating shaft, rods operatively connected with said shaft and adjustably connected 110 with parts of the frame, and yielding tension devices secured to the opposite end of the frame, substantially as specified.

5. In a wire fence machine, the combination of an oscillating frame, take-up rolls co-operating therewith, an operating shaft, rods operatively connected at one end with said shaft and at their opposite ends adjustably connected with said frame, and means for continuously operating said take-up rolls. 115

6. In a wire fence machine, the combination of pulling-out mechanism comprising an oscillating frame, adjustable connections between said frame and suitable power devices for increasing or decreasing the movement of said frame, take-up mechanism coöperating with said frame, and means for actuating such take-up mechanism. 125

7. In a wire fence machine, the combination of mechanism for feeding strand-wires, 130

mechanism for feeding stay-sections to have their ends coiled around adjacent strand-wires, pulling out mechanism comprising an oscillating frame, take-up mechanism comprising continuously operated rollers, an operating shaft, adjustable connections between said shaft and said oscillating frame, and means for actuating said rolls.

8. In a wire fence machine, the combination of a plurality of coilers through which strand-wires are fed, mechanism for feeding stay-sections in lengths to span the spaces between the strand-wires, an oscillating frame for intermittently drawing the strand-wires through the coilers, and continuously driven take-up and wrapping devices, substantially as specified.
9. In a wire fence machine, the combina-

tion of a plurality of coilers through which strand-wires are fed, mechanism for feeding stay-sections in lengths to span alternate spaces between the strand-wires, pulling-out mechanism for the strand-wires comprising a pivoted frame carrying rollers around which the wires are directed, means for oscillating the frame on its pivot, and continuously driven take-up and wrapping devices, substantially as specified.

In testimony whereof we affix our signatures, in presence of two witnesses.
